The ornamental design for a handbag raincoat, as shown and described.

DESCRIPTION

FIG. 1 is a front view of a handbag raincoat.

FIG. 2 is a back view of a handbag raincoat.

FIG. 3 is a top view of a handbag raincoat.

FIG. 4 is a bottom view of a handbag raincoat.

FIG. 5 is a side view of a handbag raincoat.

FIG. 6 is another side view of a handbag raincoat.

FIG. 7 is a perspective view of a handbag raincoat; and,

FIG. 8 is a perspective view of a handbag raincoat in an environment of use.

The smooth zigzag line along the top portion of the handbag raincoat is indicative of the joining of two sides.

The broken lines shown in the drawings are included for the purpose of illustrating environmental structure and form no part of the claimed design.
